Attorney

UNITED STATES PATENT OFFICE

WILHELM KUEHNER, OF PROVIDENCE, RHODE ISLAND

BRACELET

Application filed December 8, 1928. Serial No. 324,739.

This invention relates to certain new and useful improvements in bracelets, and the primary object thereof is to provide a bracelet of the flexible type which is of novel and improved construction and wherein the units are connected so as to afford increased flexibility while still maintaining the same in assembled and aligned relation.

A further object of the invention is to provide a bracelet wherein the units are assembled so as to impart an attractive, novel and unique appearance to the bracelet.

The invention still further aims to provide a simple and economical structure and one wherein the units can be easily and quickly assembled.

In the drawings:—

Figure 1 is a top plan view of the invention;

Figure 2 is a section on line 2—2 of Figure 1;

Figure 3 is a section on line 3—3 of Figure 1 and

Figure 4 is a fragmentary bottom plan view.

In proceeding in accordance with the present invention, a pair of laterally spaced longitudinal side elements or members 1, are employed, which members are flexible or formed of flexible material, and may be of wire rope, or link or chain construction, as preferred. As shown in Figure 3, the members are shown as of wire braid and may be of hollow or tubular formation in the interest of lightness.

A series of units 2 are employed, here shown as being of elliptical or ovaloid form, although in this regard it is to be expressly understood, that various shapes of units can be used without affecting the invention, such as diamond shape, rectangular, or the like.

The units are curved both longitudinally and transversely so as to conform to the wrist of the wearer and maybe, if desired ornamented with jewels, such as at 3, in addition to the usual familiar surface ornamentation.

Each side of each unit is formed with a transverse lug or finger 4, the lugs being beat over the side members, or strands 1, so as to secure the units thereto. As shown in the drawings, the adjacent ends of the adjacent

units freely overlap so as to present a novel and continuous surface for the bracelet, and one which at the same time does not interfere with free flexibility of the bracelet.

From the foregoing it will be seen that the units are flexibly related by virtue of the flexibility of the side strands or members, and the bracelet can, due to the overlapping of the units, readily conform itself to the wrist of the wearer. The units in addition by virtue of their overlapping relation, serve to maintain the shape of the bracelet, and mutually assist in holding one another in position.

Having thus described my invention, what I claim as new and desire to secure by Letters Patent is:—

1. A bracelet including a pair of spaced flexible side members and a series of plate-like units of concavo-convex form in both cross and longitudinal section, said units having their adjacent ends overlapping and freely movable toward and away from one another, said units having lugs on their opposite sides and at the centers of said sides which lugs are bent into engagement with the respective side members so as to provide for free relative flexing movement between the ends of the units and the side members.

2. A bracelet including a pair of spaced flexible side members and a series of plate-like units of concavo-convex form in longitudinal section, said units having their adjacent ends overlapping and freely movable toward and away from one another, and means to connect said units to each of the side members to enable free relative flexing movement between the ends of the units and the side members.

In testimony whereof I have signed my name to this specification.

WILHELM KUEHNER.
